UNITED STATES PATENT OFFICE.

CHARLES M. HORTON, OF ELIZABETH, NEW JERSEY, ASSIGNOR TO THE SINGER
MANUFACTURING COMPANY, A CORPORATION OF NEW JERSEY.

MULTIPLE TUCKING-GUIDE FOR SEWING-MACHINES.

1,152,635.

Specification of Letters Patent.

Patented Sept. 7, 1915.

Application filed August 23, 1911. Serial No. 645,606.

To all whom it may concern:

Be it known that I, CHARLES M. HORTON, a citizen of the United States, residing at Elizabeth, in the county of Union and State 5 of New Jersey, have invented certain new and useful Improvements in Multiple Tucking-Guides for Sewing-Machines, of which the following is a specification, reference being had therein to the accompanying 10 drawings.

This invention has for its object to facilitate the construction of multiple-tuck-fold- 15 ing devices for sewing machines, to insure a lightness of construction thereof for convenient manipulation, to increase the rigidity 20 of the separable upper and lower members and to support the upper members in such manner as to avoid interference with the lead of the threads of multiple-needle sewing machines to which they are commonly applied.

As preferably constructed the device comprises a lower series of detached, spaced and convergent forming-bars rigidly connected 25 together and each sustaining at its delivery end a forwardly and laterally extending tuck-supporting wing connected along one edge with the adjacent edge of a twisted tuck-bending wing constituting a continua- 30 tion of the forming-bar with its farther extremity turned into transverse relation therewith, and an upper series of detached, spaced and convergent oppositely directed forming-bars entering the spaces between 35 the bars of the lower series and rigidly connected together, means being provided for rigidly connecting the upper and lower series of forming-bars at opposite sides there- 40 of. Each of the forming-bars is preferably constructed from a sheet metal blank bent into substantially U-shaped cross-section, the lower bars each having one limb extended forwardly from the body portion and being shaped to form the described support- 45 ing and bending wings. These bars are usually formed separately and secured in spaced relation to cross-bars, and the upper and lower of each are connected together at their opposite ends for independent adjustment to insure the requisite spacing apart of the upper and lower series of forming- 50 bars to properly admit between them the fabric to be successively crimped and folded.

The component tuck-forming bars of the

opposed series are formed individually or 55 separately from each other, and are not only spaced apart, but are mutually unconnected at their bases or wider portions of their cross section throughout the greater portion of their length and excepting where they are 60 overlaid by cross bars by which they are secured together, and preferably detachably. These bars are preferably made from sheet metal blanks in U-shaped cross section, so 65 that they are hollow throughout their lengths, excepting where reinforced to receive the fastening means. By this means the attachment is given a lightness of construction which is not attained with series 70 of forming bars cast integral and connected at the bases throughout their length as heretofore.

The invention will be more fully understood by reference to the accompanying drawings, in which—

Figure 1 is a front end elevation of a multiple-needle sewing machine constructed in accordance with the application of Philip Diehl and Hermann Eichhorn, Serial No. 595,356, filed December 3, 1910, and pro- 80 vided with the present improvement, and Fig. 2 is an elevation of the tucking attachment viewed from the delivery end. Fig. 3 is a plan of a portion of the sewing machine bed-plate and the tucking attachment ap- 85 plied thereto, and Fig. 4 an end view of the same with the attachment partially in section. Fig. 5 is a transverse sectional view of the attachment with the fabric in position. Fig. 6 is a plan of a blank for one of 90 the lower forming-bars and Fig. 7 a perspective view of the bar bent into the required shape. Fig. 8 is a perspective view of one of the tuck-guides for directing the folds to the stitch-forming mechanism. Fig. 9 is 95 a perspective view of a section of fabric folded and stitched by the use of the present improvement.

The sewing machine is shown constructed with a hollow base 1 and a head comprising 100 the bed-plate 2 and bracket-arm 3 in the head of which is journaled the reciprocating needle-bar 4 carrying a series of needles 5 arranged transversely of the direction of feed, which is cross-wise of the bed-plate. 105 The presser-bar 6, also journaled in the head of the bracket-arm, is pressed downwardly by means of a spring 7 resting upon the up-

per end of the same, and has secured to its lower end the shanks 8 of the tilting presser-
feet 9 normally resting upon the top of the raised portion 10 of the throat-plate 11 secured upon the bed-plate 2. The throat-plate is provided with a series of needle-apertures 13 and feed-dog apertures 14 to accommodate the feed-dogs 15.

Secured to the front of the base 1 are the brackets 16 whose upper members are channeled to receive the bars 17 connected at the outer ends by tie-bars 17^x and affording a means of support for the attachment.

As represented more particularly in Fig. 3, the tuck-forming bars of each series, while similar in general form, are shaped individually to suit the respective positions which they occupy in the attachment.

Fig. 6 represents the sheet metal blank 20 from which the central lower forming-bar is made. This blank has a body portion *a* of taper form having a longitudinal extension *b* on one side of the center of its larger end and an adjacent lateral extension *c* adjoining the same and at the same side of the body portion.

The body portion of the blank is bent into substantially U-shaped cross-section to produce the forming-bar which is shallow at 30 the rounded narrower end of the blank and increases in depth while decreasing in width toward the opposite end so as to form at the top a rounded convergent fabric-bending face 18 merging into the flat side faces 19 and 20 with their lower edges at what may be termed the base of the bar. The lateral extension *c* of the blank is bent at substantially a right angle to the adjacent face 20 of the body portion to form the tuck-supporting 40 wing 21, and the adjacent extension *b*, which forms a continuation of the face 20, is twisted into the tuck-bending wing 22 whose forward extremity is offset above the wing 21 and has a slight upward inclination relative thereto, as represented more particularly in Fig. 2.

The upper tuck-forming bars are similarly constructed from sheet metal blanks similar in general shape to that represented in Fig. 6 but lacking the extensions *b* and *c*. These are also bent into substantially U-shaped and taper form, increasing in depth from receiving to delivery end, and are sustained in the attachment in inverted position with their rounded fabric-bending faces 23 disposed intermediate and below and spaced from the corresponding portions 18 of the lower bars and their opposite side faces 24 and 25 substantially parallel with 55 but separated from the corresponding faces of the lower bars, as represented in Fig. 5.

Fitted within and firmly secured to the lower hollow forming-bars are the blocks 26 and 27, into which are tapped the fastening screws 28 passing through slots 29 in the

cross-bars 30 and 31 by means of which the forming-bars are secured for lateral adjustment in spaced relation upon the cross-bars.

The hollow upper forming-bars are similarly provided with the blocks 32 and 33 into which are tapped the fastening screws 34 which pass through slots 35 in the cross-bars 36 and 37, respectively, by means of which the upper tuck-forming bars are rigidly and adjustably secured in spaced relation to the cross-bars 36 and 37.

At its opposite ends, the cross-bar 36 has tapped through the same the spacing screws 38 whose points rest upon the top of the lower cross-bar 30, while a clamp-screw 39 passing loosely through the upper cross-bar is tapped into the lower cross-bar so as to hold the points of the spacing screws 38 firmly seated upon the lower cross-bar, thereby providing means for adjustably securing the upper and lower series of forming-bars in operative relation. Passing loosely through apertures in the opposite ends of the upper cross-bars 37 are the spacing screws 40 formed with necked heads 41 and tapped into the lower cross-bars 31 beneath which they are provided with the jam-nuts 42. The necked portion of each screw-head is embraced by the slotted offset portion 44 of a swivel-plate 45 secured to 95 the upper cross-bar for sustaining the spacing screw 40 against endwise movement in the latter. The screws 40 thus operate to maintain the receiving end portions of the upper and lower forming-bars adjustably in 100 the required relation.

It is evident that the described connecting means for one pair of upper and lower cross-bars may be used for connecting the other pair, but in any case it is desirable that these cross-bars should be independently adjustable in order, not only to change the spacing apart of the upper and lower series of tuck-forming members to accommodate different thicknesses of fabric, but to adjust the angular relation of such members under different conditions.

The lower faces of the tuck-supporting wings 21 and the lateral extensions 19^x and 20^x of the lower tuck-forming bars are secured by soldering, or otherwise, upon a thin transverse plate 46 by means of which the delivery portions of the lower series of forming-bars are firmly secured together. The attachment rests mainly upon the sustaining bars 17 and is secured in operative relation with the stitch-forming mechanism secured in position by means of the fastening screws 48 passing through the extensions 19^x and 20^x and tapped into the bed-plate 2, as represented more particularly in 125 Fig. 3.

Secured upon the forward upper cross-bar 36 by means of the screws 49 are the forwardly extending strips 50 carrying the 130

cross-rod 51 in which are secured the round shanks 52 of the tuck-guiding blades 53 which are provided with the lateral wings 54 projecting beneath the tuck-bending wings 22 and whose other edges 54^x are adapted to enter the angles of the bases of the tucks with the body fabric to guide the same to the stitch-forming mechanisms. The guiding edge 54^x of each wing 54 is disposed upon the opposite side of the needle-path from the body of the tuck-guide.

The upper tuck-forming bars are preferably made somewhat shorter than the lower for convenience in introducing the fabric *m*, the forward edge of which is placed upon the outer extremities of the lower forming-bars and pushed forwardly by pressure of the same by the fingers of the operator upon the operative portions 18 of the lower bars intermediate the upper bars until the progressively crimped advance portion of the fabric becomes sharply folded into standing tucks at the delivery ends of the lower forming-bars from which they are delivered upon the twisted bending wings 22 and introduced beneath the raised presser-foot 9, the angles of the tucks *t* with the adjacent body portions *f* of the fabric having been delivered by the upper forming-bars upon the tuck-guiding wings 54, whose guiding edges 54^x serve to present to the respective needles of the stitch-forming mechanism the bases of the tucks *t* to be stitched upon the adjacent body portions of the fabric. The presser-foot having been lowered, the sewing machine is operated in the usual manner to draw the work through the attachment as represented in Fig. 5, and stitch the several tucks therein by lines of stitches *s*, as represented in Fig. 9.

It has been found in practice impracticable to employ in the initial crimping and folding operation thin forming-blades with sharp edges presented to the fabric, for the reason that the latter is required to be drawn inwardly from the flat condition in which it enters the folder into a series of folds, the material moving across the bending portions 18 and 23 of the lower and upper tuck forming-bars, respectively, while traveling lengthwise of the same. The presentation of abrupt operative edges to the opposite faces of the fabric in this operation would cause the creasing or puckering of the fabric and its imperfect delivery to the stitch-forming mechanism, but by employment of the rounded forming-members this imperfect handling of the work is avoided.

It has heretofore been common, as shown in the United States patent to Foster, No. 575,342, of January 19, 1897, to form series of upper and lower tuck-forming members in upper and lower solid plates; by an apparatus for forming simultaneously a large number of tucks, a defect in one of

these members necessitated replacement of the whole forming plate with another, whereas according to the present improvement the bars are constructed separately or in groups or only a few connected together, thereby saving the large amount of labor and material under such conditions. The construction of the several bars of sheet metal separately serves materially to lighten the structure without in any way injuring its effectiveness.

It has heretofore been the practice, as shown in the patent before mentioned, to sustain the upper tuck-forming members from the head of the bracket-arm of the machine, and independently of the lower forming-bars. This expedient required the special fitting of the bracket-arm head as well as the lower part of the machine frame to accommodate the different parts of the attachment, whereas according to the present improvement the attachment is self-contained and is adapted to be fitted to a single part of the machine, while its component members are adapted to be more directly and more rigidly secured together for co-operation in performing their several functions.

In the multiple-needle machine shown in Fig. 1 the needle threads *n* are led from the source of supply through their respective tensions and through apertures in the cross-bar 55 upon the needle-bar and thence through a guide-bar 56 secured upon the front of the bracket-arm head from which they are led to the needles. With machines of this type employing a large number of needles and employed in the production simultaneously of a corresponding number of tucks, the leading of the upper threads to the needles down the front of the bracket-arm head renders it impracticable to secure to the latter a bracket holding with sufficient rigidity the upper tuck-forming members, and by mounting such members upon cross-bars secured at their opposite extremities upon similar cross-bars connecting the lower forming-members this difficulty is overcome and ample space is provided at opposite sides of the forming members for those portions of the body fabric adjoining the tucked portion.

It is evident that the several features of the present improvement may be used separately and that the component parts of the apparatus, as above described, may be materially modified in construction and arrangement without departure from the scope of the present invention.

Having thus set forth the nature of the invention, what I claim herein is:—

1. A tuck-forming attachment for sewing machines, comprising a lower series of separate spaced and convergent forming-bars rigidly connected together and each having

at its delivery end a laterally twisted wing with that portion thereof immediately adjacent said forming bar in alinement with one face of the bar and with the extremity of said twisted wing arranged transversely to the same face of the bar, an upper series of spaced and convergent forming-bars entering the spaces between the bars of the lower series and rigidly connected together, 10 a series of tuck-guides disposed in register with the upper forming-bars and adapted to guide the bases of the tucks to the stitch-forming mechanism, a rigid connection between said tuck-guides and the upper forming-bars, and means arranged at opposite sides of the series of upper and lower tuck-forming bars for adjustably securing the same together in fixed relation.

2. A tuck-forming attachment for sewing 20 machines, comprising a lower series of separate spaced and convergent forming-bars rigidly connected together and each having at its delivery end a laterally twisted wing with that portion thereof immediately adjacent said forming bar in alinement with one face of the bar and with the extremity of said twisted wing arranged transversely to the same face of the bar, an upper series of spaced and convergent forming-bars entering the spaces between the bars of the lower series and rigidly connected together, a series of tuck-guides disposed in register with the upper forming-bars and adapted to guide the bases of the tucks to the stitch-forming mechanism, and means for adjusting both the angular relation and the spacing apart of the upper and lower series of tuck-forming bars.

3. A tuck-forming attachment for sewing 40 machines comprising a lower series of separate, spaced and convergent forming-bars mutually unconnected at their bases throughout the greater portion of their length and each having at its delivery end and at one side thereof a flat laterally extending wing and above the same extending from the opposite side a laterally twisted wing with that portion thereof immediately adjacent said forming bar in alinement with one face of the bar and with the extremity of said twisted wing arranged transversely to the same face of the bar, the bases of said bars being separated by an intervening opening throughout that part of the length of each 50 from said wings at the delivery end to the opposite end, an upper series of separate and similarly spaced and convergent forming bars also mutually unconnected at their bases throughout the greater portion of their length and entering the spaces between the bars of the lower series, means for sustaining the upper and lower series of the forming bars, and means for delivery of tucks 60 from said bars in parallelism.

4. A tuck-forming attachment for sewing

machines comprising a lower series of separate, spaced and convergent forming-bars mutually unconnected at their bases through the greater portion of their length and each having at its delivery end and at one side thereof a flat laterally extending wing and above the same extending from the opposite side a laterally twisted wing with that portion thereof immediately adjacent said forming bar in alinement with one face of the bar and with the extremity of said twisted wing arranged transversely to the same face of the bar, the bases of said bars being separated by an intervening opening throughout that part of the length of each 70 from said wings at the delivery end to the opposite end, an upper series of separate and similarly spaced and convergent forming-bars also mutually unconnected at their bases throughout the greater portion of their length and entering the spaces between the bars of the lower series, a series of tuck-guides disposed in register with the upper forming-bars and adapted to guide the bases of the tucks therefrom to the stitch-forming 80 mechanism, and means for rigidly connecting together the component forming-bars of each series.

5. A tuck-forming attachment for sewing machines comprising a lower series of 90 spaced forming-bars hollow throughout the greater portion of their length and rigidly connected together and each formed of substantially inverted U-shaped cross-section with a flat lateral wing extending forwardly 100 from the edge of the extremity of one member and a twisted wing extending forwardly from the same member and turned oppositely from said lateral wing at its forward end into transverse relation with said member and offset above said lateral wing, and an upper series of forming-bars also hollow throughout the greater portion of their length and of substantially U-shaped cross-section entering the spaces between the bars 110 of the lower series and rigidly connected together.

6. A tuck-forming attachment for sewing machines comprising a series of separate spaced and convergent forming elements of 115 U-shaped cross-section, a series of spaced and convergent forming elements of U-shaped cross-section entering the spaces between the elements of the first-named series, means separate from and overlying said elements for rigidly sustaining each forming element of each series relatively to the others, and means whereby the tucks are delivered from said forming elements in parallelism.

7. A tuck-forming attachment for sewing machines comprising a series of separate spaced and convergent forming elements of U-shaped cross-section merging at one extremity into flat cross section with oppo- 130

sitely extending lateral wings, a series of spaced and convergent forming elements of U-shaped cross-section entering the spaces between the elements of the first-named series, 5 means separate from and disposed crosswise of said elements for rigidly sustaining each forming element of each series relatively to the others, and means coöperating with said lateral wings whereby the tucks are deliv-

ered from said forming elements in parallelism.

In testimony whereof, I have signed my name to this specification, in the presence of two subscribing witnesses.
